US00D443695S

(12) **United States Design Patent** (10) Patent No.: **US D443,695 S**
 Heitz et al. (45) Date of Patent: ** Jun. 12, 2001

(54) CONTAINER FOR DIAGNOSTIC ANALYZER	5,147,272	9/1992	Richison et al. .
(75) Inventors: Bernhard H. Heitz; Rickey D. Burns, both of Roswell, GA (US)	5,254,073	10/1993	Richison et al. .
(73) Assignee: AVL Medical Instruments, Schaffhausen (CH)	5,279,797	1/1994	Burns et al. .
(**) Term: 14 Years	5,417,121	* 5/1995	Andersen et al. 73/864.22
(21) Appl. No.: 29/123,892	5,501,982	3/1996	Saldivar, Jr. et al. .
(22) Filed: May 26, 2000	5,542,902	8/1996	Richison et al. .
(51) LOC (7) Cl. 24-02	5,665,315	* 9/1997	Robert et al. 422/102
(52) U.S. Cl. D24/224	5,777,202	7/1998	Betts et al. .
(58) Field of Search D24/224, 216, D24/121; 422/102, 101, 103, 104, 61; 220/221, 403, 404; 204/401, 403; 73/862.51, 862.62, 862.22, 862.81	5,820,825	10/1998	Weinzierl et al. .
	5,882,602	3/1999	Savage et al. .
	5,885,533	3/1999	Savage et al. .
	5,913,232	6/1999	Betts et al. .
	5,980,830	11/1999	Savage et al. .
	5,985,218	11/1999	Goodale .
	5,986,453	10/1999	Shugart .
	6,016,683	1/2000	Betts et al. .
	6,178,832	* 1/2001	Mathur et al. 73/864.62
